UNITED STATES PATENT OFFICE.

JEROME J. AULL, OF CINCINNATI, OHIO, ASSIGNOR TO THE LUNKENHEIMER COMPANY, OF CINCINNATI, OHIO, A CORPORATION OF OHIO.

DESIGN FOR A VALVE-WHEEL.

45,142.

Specification for Design.

Patented Jan. 13, 1914.

Application filed October 23, 1912. Serial No. 727,444. Term of patent 14 years.

To all whom it may concern:

Be it known that I, JEROME J. AULL, a citizen of the United States, and a resident of the city of Cincinnati, in the county of Hamilton and State of Ohio, have invented a new, original, and ornamental Design for Valve-Wheels, of which the following is a specification, reference being had to the accompanying drawing, forming part thereof.

Figure 1 is a perspective view of a valve

wheel, showing my new design. Fig. 2 is a central cross section of the same.

I claim:

The ornamental design for a valve wheel, as shown.

JEROME J. AULL.

Witnesses:

C. A. DAVIES,
BERT HALLER.
